[57] **ABSTRACT**

An extensive series of quinoline derivatives is disclosed, more particularly several 5,7-bichloro-8-hydroxy-quinolines carrying various substituents in the 2-position. The most interesting substituents are the aldehyde grouping, the amino grouping, the alkylaminic groupings, the piperidino, morpholino and piperazino groupings as such and variously substituted, the halogenacetic groupings, the acylaminic groupings and the halogenalkylic grouping, and also the alcoholic radicals. These compounds have proven to be very effective antiseptics and fungicides.

**5,7-BICHLORO-8-HYDROXY-2-ACETYLAMINO
QUINOLINE**

BACKGROUND OF THE INVENTION

FIELD OF THE INVENTION

This invention relates to a few quinoline derivatives which are useful as antiseptics and fungicides.

More particularly, the invention is concerned with a few 5,7-bichloro-8-hydroxy quinolines with various substituents in the 2-position of the quinoline ring.

The considerable reactivity of 8-hydroxy-quinoline was already known, said reactivity being manifested by the ability of this compound to form metal chelates, especially with heavy metals: for this reason, the 8-hydroxy quinoline is still used in analytical chemistry as a reactive for heavy metals.

More particularly, the object of the laborious experimental work which led to the preparation of a large number of derivatives of the 5,7-bichloro-8-hydroxy quinoline, has been to offer, to the clinical practitioners, sophisticated weapons for combating several syndromes either due to bacteria or to fungi.

Thus, numerous compounds have been prepared, which have in common the 5,7-bichloro-8-hydroxy quinoline skeleton and differ from each other by the different substituents in the 2-position.

The 2-position substituents which are conducive to the most interesting compounds to the ends of the present invention are the following: the aldehyde grouping, the amino grouping, the alkylaminic groupings, the piperidino, piperazino and morpholino grouping, either as such or variously substituted, the halogen-acetylic groupings, the acylaminic groupings and the halogenoalkyl groupings, and the alcoholic radicals as well.

In the light of the foregoing, the compounds which are most interesting from a pharmacological standpoint, as prepared according to the teachings of the present invention, are the following:

In the first place, the

5,7-bichloro-8-hydroxy-2-piperidinomethyl-quinoline, and:

5,7-bichloro-8-hydroxy-2-diethylaminomethyl-quinoline

5,7-bichloro-8-hydroxy-2-morpholinomethyl-quinoline

5,7-bichloro-8-hydroxy-2-acetylamino-quinoline

5,7-bichloro-8-hydroxy-2-quinaldehyde

5,7-bichloro-8-hydroxy-2-amino-quinoline

5,7-bichloro-8-hydroxy-2-(4-methyl)-piperazinomethyl-quinoline

5,7-bichloro-8-hydroxy-2-quinolinemethanol

5,7-bichloro-8-hydroxy-2-diethylaminoethyl-quinoline

5,7-bichloro-8-hydroxy-2-chloroacetyl-quinoline

5,7-bichloro-8-hydroxy-2-chloromethyl-quinoline.

It is quite obvious that, to prepare so wide a range of derivatives with substituents which are so sharply different from each other, it is impossible to suggest a single reaction scheme for the process of preparation. Instead, it will be pointed out, at the outset, that the several methods selected for the preparation of the different quinoline derivatives in question, are not critical per se and have been given in this specification by way of example only, in order to show in a comprehensive

manner how their preparation can be arrived at with means which are, however, simple enough when they are compared with the complex nature of the compounds involved and of the numerous and various substituents.

BRIEF DESCRIPTION OF THE DRAWINGS

For these reasons, it has been deemed expedient, in order to enable the reader to follow a convenient guideline of logical classification, to accompany the examples given in the following, with the, so to speak, "genealogical" patterns of FIGS. 1 and 2 in order to allow the identification, for each compound, of the better way which is suggested to arrive, individually, to the compound one wishes to prepare.

As a general information criterion, it can be said that the starting point of the reaction patterns indicated in FIGS. 1 and 2 is chloro-quinadol, or 5,7-bichloro-8-hydroxy quinaldine. Using it as the starting compound, the benzyl derivatives are first prepared, that is, those which contain, in the 8-position, the grouping $-\text{O}-\text{CH}_2-\text{C}_6\text{H}_5$. From the latter compounds, in which has been introduced, at the proper time, in the 2-position, the functional grouping involved, selected among those listed hereinabove, one arrives, through a debenzylation, to the quinoline derivatives which contain, in the 2-position, the desired radical.

In order to simplify the reaction patterns, the following symbols have been adopted in the graphical representation of FIGS. 1 and 2:

35

50

55

60

65

Numerous examples will now be given, which correspond to the reaction patterns of FIGS. 1 and 2: it should be noticed that each of the compounds prepared with the reactions of the above indicated patterns has been numbered, both in the FIGS. and in the description of the examples, with a Roman numerical so as to enable anyone to find immediately and to recognize in the pattern, the sequence of reactions adapted to prepare the desired compound. It should be noticed, again, that the reaction patterns of FIGS. 1 and 2 are merely exemplary, in that the compounds concerned, or, at least, a certain number thereof, could also be prepared otherwise. In the example concerned herein, there has been selected, for each individual compound, the way which has been deemed the shortest and the most convenient to prepare it.

DETAILED DESCRIPTION OF THE PREFERRED EMBODIMENTS AND EXAMPLES

5,7-BICHLORO-8-BENZYLOXY QUINALDINE

Twelve (12) grs. chloroquinaldol are slowly introduced in a solution of 3.6 grs. KOH in 600 mls. ethanol, maintained at 70° C. Upon total dissolution, 7.4 mls. of alpha-bromo-toluene are added dropwise with stirring and the solution is refluxed during 3 hours. Upon cooling, a filtering step is carried out and the filtrate is concentrated in a vacuo to dryness. The semi-solid substance thus obtained is taken up with ethyl acetate: the inorganic portion which is still present is filtered and the solution concentrated once more. The oily residue is distilled and the fraction between 190° C and 200° C (11 millimeters of mercury) is collected and taken up with 20 mls. of hot ethanol. Upon cooling, the crystallize is collected on a filter and there are obtained 10 grs. of a product having a m.p. of 62°-63° C, which, however, is still slightly impure due to chloroquinaldol.

For C₁₇H₁₃Cl₂NO:Found: Cl% = 22.28
Calcd. 22.50

5,7-BICHLORO-8-BENZYLOXY-2-QUINOLINE ALDEHYDE

To a solution of 6.73 grs. of SeO₂ in 140 mls. dioxane and 14 mls. water, heated on a boiling water bath, there are added, all at a time 14 grs. of 5,7 dichloro-8-benzyloxy quinaldine dissolved in 140 mls. dioxane. Upon stirring, in hot condition, during 3 hrs., the solution is filtered, cooled and the filtrate is concentrated in a vacuo. The residue, recrystallized from ligroin, melts at 125° C. 13 Yield: 12 grs.

For C₁₇H₁₁Cl₂NO₂Found: C% = 61.34; H% = 3.41
Calcd. 61.46 3.34
Found: N% = 4.16 Cl% = 21.21
Calcd. 4.22 21.35

5,7-BICHLORO-8-BENZYLOXY-2-QUINOLINECARBONIC ACID

To a suspension of 2 grs. of 5,7-benzyloxy-2-quinoline aldehyde in 140 mls. of a 7.5 percent aqueous solution of NaOH kept on a water bath at 80° C, is slowly added, with stirring, a solution of 20 mls. hydrogen peroxide (120 volumes) in 20 mls. water. After 2 hrs. at 80° C, the solution is allowed to cool and the sodium salt of the acid is filtered and dissolved in hot condition in an aqueous solution of sodium carbonate. Upon filtration, the cool filtrate is acidified with glacial acetic acid. The solid ppte., collected on a filter, is thoroughly washed with water, dried and recrystallized from ligroin. There are obtained 11 grs. of a product having a m.p. of 148° C-149° C.

For C₁₇H₁₁Cl₂NO₃Found C% = 58.57; H% = 3.34; N% = 4.07; Cl% 20.60
Calcd. 58.64 3.19 4.02 20.3%

5,7-BICHLORO-8-BENZYLOXY-2-QUINOLINECARBONIC ACID CHLORIDE (XV)

A mixture of 5 grs. of 5,7-dichloro-8-benzyloxy-2-quinoline carbonic acid and 6 grs. of PCl₅ in 300 mls. of CCl₄ is refluxed during 5 hours. Upon cooling, the solvent is evaporated in a vacuo and the residue taken up with anhydrous ether. The inorganic portion is removed by filtration and the liquor is concentrated again, the residue is recrystallized from ligroin and gives 3.8 grs. of a yellow crystalline product having a m.p. of 132° C-133° C.

For C₁₇H₁₀Cl₃NO₂

15	Found N% = 4.01 Calcd. 3.82	Cl% = 29.12 29.01

5,7-BICHLORO-8-BENZYLOXY-2-QUINOLINECARBONIC ACID AZIDE

To a solution of 1 gr. of 5,7-dichloro-8-diethylaminoethyl-2-quinoline carbonic acid chloride in 70 mls. acetone is slowly added, at room temperature, a solution of 0.72 grs. NaN₃ dissolved in 10 mls. water. After 1 hour, the mixture is poured, with stirring at room temperature, in iced water and the solid which has been formed is collected on a filter. A product is obtained, which has a satisfactory infrared spectrum but is slightly impure and has a m.p. of 125° C-127° C. It is, however, sufficiently pure for the subsequent reactions.

For C₁₇H₁₀Cl₂N₂O₂

35	Found N% = 13.60 15.01	Cl% = 19.14 19.00

5,7-BICHLORO-8-BENZYLOXY-2-AMINOQUINOLINE

40 A solution of 4.4 grs. of 5,7-dichloro-8-benzyloxy-2-quinoline carbonic acid azide dissolved in 650 mls. anhydrous dioxane (0.17 percent water) is refluxed during 5 hours. The solution is evaporated to dryness in a vacuo and from the residue, recrystallized from aqueous ethanol, 2.3 grs. of substance are obtained. m.p. 188° C-189° C.

For C₁₈H₁₂Cl₂N₂O

50	Found N% = 8.68 Calcd. 8.78	Cl% = 22.10 22.22

The hydrochloride, recrystallized from ethanol, melts at 158° C-160° C.

55 For C₁₈H₁₂Cl₂N₂O . HCl

Calcd.	53.87 54.03	H% = 3.94 3.69	N% = 7.77 7.88	Cl% = 29.42 29.90

5,7-BICHLORO-8-HYDROXY-2-AMINOQUINOLINE

60 2.3 grs. of 5,7-dichloro-8benzyloxy-2-aminoquinoline in 15 mls. conc.HCl are allowed to stand at room temperature during 2 days. The solution is evaporated to dryness under reduced pressures, the residue is taken up with an aqueous solution of sodium bicarbonate and the obtained ppte. is collected on a filter. The ppte. is thoroughly washed with water and dried

and is converted into a hydrochloride with alcohol, hydrochloric acid and precipitated with ether.

By recrystallization from ethanol there are obtained 0.13 grs. of a substance having a m.p. of 300° C-303° C.

For $C_9H_8Cl_2N_2O \cdot HCl$
Found C% = 40.76; H% = 2.96; N% = 10.35; Cl% = 40.09
Calcd. 40.70 2.66 10.55 40.06

The base, recrystallized from ethanol, melts at 234° C-235° C.

For $C_9H_8Cl_2N_2O$
Found C% = 47.55; H% = 2.66; N% = 12.11; Cl% = 30.70
Calcd. 47.19 2.64 12.23 30.96

5,7-BICHLOORO-8-BENZYLOXY-2-ACETYLAMINOQUINOLINE

4.5 grs. of 5,7-dichloro-8-benzyloxy-2-aminoquinoline, free base in 350 mls. acetic anhydride are stirred during 3 hours on a water bath kept at 90° C. Upon cooling, the solvent is evaporated in a vacuo. The solid thus obtained, by taking up the residue with water, is collected on a filter and, after several washings with water, is recrystallized from aqueous ethanol. Yield 3 grs. — m.p. 142° C-143° C

For $C_{18}H_{14}Cl_2N_2O_2$
Found C% = 60.04 H% = 4.01 N% = 7.45 Cl% = 19.58
Calcd. 59.85 3.90 7.76 19.63

5,7-BICHLOORO-8-HYDROXY-2-ACETYLAMINOQUINOLINONE

0.6 grs. of 5,7-dichloro-8-benzyloxy-2-acetylaminoquinoline in 50 mls. of conc. HCl are allowed to stand during 4 days at room temperature. The solution is poured in water and the solid precipitate, thoroughly washed with water, is recrystallized from aqueous ethanol. 0.180 grs. of product, having a m.p. of 223° C-224° C are obtained.

For $C_{11}H_8Cl_2N_2O_2$
Found C% = 48.75 H% = 3.03 N% = 9.58 Cl% = 20.35
Calcd. 48.73 2.97 10.34 20.16

5,7-BICHLOORO-8-BENZYLOXY-2-QUINOLINEMETHANOL

To a solution of 3.5 grs. of 5,7-dichloro-8-benzyloxy-2-quinoline aldehyde in 350 mls. of methanol, kept at 50° C, are slowly added, with stirring, 2.04 grs. of $NaBH_4$ dissolved in 25 mls. water. After refluxing during 4 hours, the cool solution is filtered and concen-

For $C_{11}H_8Cl_2N_2O_2$
Found C% = 61.25 H% = 4.05 N% = 4.21 Cl% = 21.10
Calcd. 61.09 3.92 4.19 21.22

5,7-BICHLOORO-8-BENZYLOXY-2-CHLOROMETHYL QUINOLINE

9 grs. of 5,7-dichloro-8-benzyloxy-2-quinolinemethanol and 4.5 grs. of PCl_5 in 300 mls. $CHCl_3$ are refluxed, with stirring, during 5 hours. Upon cooling, the solution is concentrated in a vacuo and the residue which has been obtained is taken up with water and extracted with ether. The extracts, after several washings with water and filtration over charcoal, are evaporated in a vacuo. The residue, recrystallized from hexane, melts at 93° C-94° C — Yield 6.1 grs.

For $C_{11}H_8Cl_3NO$
Found C% = 58.41 H% = 3.35 N% = 4.29 Cl% = 30.48
Calcd. 57.90 3.97 3.97 30.16

5,7-BICHLOORO-8-BENZYLOXY-2-TERT.AMINO METHYLQUINOLINE

To a solution of 2.84 millimoles of 5,7-dichloro-8-benzyloxy-2-chloromethyl quinoline in 15 mls. of ethyl acetate are slowly added 8.52 millimoles of an amine dissolved in 5 mls. of ethyl acetate. The mixture is refluxed during 7 hours and, upon cooling, is poured in 200 mls. ether. The solid precipitate is collected on a filter, thoroughly washed with ether and the ethereal solutions are combined and, after several washings with water, are dried over Na_2SO_4 and evaporated under reduced pressures. The residue, converted into a hydrochloride, is purified by reprecipitation from alcohol and ether. The melting points and analyses are reported in Table B.

5,7-BICHLOORO-8-HYDROXY-2-TERT.AMINO METHYLQUINOLINE

One millimole of aminobenzylate is allowed to stand during 4 hours at room temperature in 20 mls. of conc. HCl. The solution, poured in iced water, is brought to a slightly alkaline pH value with diluted soda and extracted with ethyl acetate. The extracts, washed with water and dried, are evaporated in a vacuo. The residue is converted into a hydrochloride and purified by recrystallizing it from ethanol.

The melting points and analyses of the compounds are reported in Table B.
